FEED ROLL ASSEMBLY

Albert E. Winslow, Norwich, Conn., assignor, by
mesne assignments, to Universal Winding Com-
pany, Cranston, R. I., a corporation of Massa-
chusetts

Application May 2, 1946, Serial No. 666,726

6 Claims. (Cl. 57—82)

1

This invention relates to feed rolls for feeding yarn in a textile apparatus. It is particularly designed for use on a twisting frame.

In the use of a feed roll for feeding yarn in such places as on a twisting frame, it has been usual to stop the action of the feed roll when any one of the ends which leads to the feed roll breaks by moving the feed roll itself so that it is lifted out of driving engagement with some means for driving the same. In many instances, such movement causes other yarn ends to break, in addition to the yarn end which has been broken, because of such action. In some cases slack appears in the yarn which is undesirable from the standpoint of uniform yarn, particularly in a twister.

One of the objects of this invention is to provide a feeding unit which will be individual for each of the plied yarn ends and to so arrange this unit that, if one yarn end breaks, the unit will become inoperative, while other similar units on the frame will continue to operate.

Another object of this invention is to provide a feeding means which will maintain the feed rolls the same distance from the take-up package at all times, and thus prevent any slack occurring in the yarn between the feed rolls and the supply package when one of the yarn ends breaks.

Another object of this invention is to provide a unit which will be entirely contained within a casing with all operating parts completely housed therein, and which unit may be disconnected from the apparatus or mounted on the apparatus as a unit.

Another object of this invention is to provide a feeding unit which will maintain itself fixed on the frame of the apparatus which supports the working parts of the whole structure.

With these and other objects in view, the invention consists of certain novel features of construction, as will be more fully described and particularly pointed out in the appended claims.

In the accompanying drawings:

Fig. 1 is an elevation of the upper part of a twisting frame showing my invention as applied thereto;

Fig. 2 is a top plan view showing the unit which is the subject of this invention;

Fig. 3 is a sectional view of the unit on a much larger scale than that shown in Fig. 1 with portions of the twisting frame in their operative relation thereto;

Fig. 4 is a fragmental view through the drive shaft illustrating the eccentric mounting of a gear thereon.

2

Fig. 5 is an end view of the eccentric member. Figs. 6 and 7 are sectional views on lines 6—6, and 7—7 of Fig. 4;

Fig. 8 is a sectional view through the unit illustrating the relation of the parts when moved to inoperative position; and

Fig. 9 is a fragmental sectional view illustrating the means for disconnecting the drive of the take-up spindle from its driving belt.

Fig. 10 is a fragmental face view of a part of a frame showing one unit of the apparatus.

In proceeding with this invention, I provide a unit containing feed rolls for the yarn, with a means consisting of gears on the axes of the feed rolls for driving the same while another gear is movable into and out of engagement with one of the gears on the feed rolls for driving or disconnecting the drive from the power shaft to the same. A control means is provided which is driven by the yarn which is fed, so that upon breaking of the yarn forces are brought into action to disconnect the driving gear from driving the feed rolls. By this arrangement, the feed rolls are maintained in a fixed relation to a take-up package and no slack can occur between the feed rolls and the take-up package because the axes are a constant distance apart. To move this gear out of engagement, a latch is tripped, and, as the gear is drawn out of engagement, a plunger operates to also move the take-up spindle from its driving relation to its drive belt, so that the take-up spindle is also rendered inoperative.

With reference to the drawings, a part of a twisting frame which is pertinent to this invention is illustrated in Fig. 1, wherein there is shown a post 10, which is mounted on a frame 11 for the back to back mounting of operating parts of the machine and which in turn mounts a bracket 12 also for supporting in back to back relation the individual feeding and guiding yarn end mechanisms. A further bracket 13 is mounted above this bracket 12 for the support of certain trip mechanisms for the stop motion operation.

Each spindle assembly is mounted on a fixed spindle rail 27 which is a part of the framework of the machine. Separators 28 are positioned between the spindles so as to prevent the engagement of the balloon of the yarn about one spindle with the yarn which balloons about another spindle. The spindle 29 has a whorl 26, and is mounted on a swinging arm 22 (see Fig. 9) which is swung by a concealed spring in a housing 23 into engagement with a belt 24. A brake

25 is so positioned that the arm 22 may cause the whorl 21 to be swung into engagement therewith when removed from driving engagement with the belt 24. A back-up roll 26 (see Fig. 1) is provided adjacent to belt 24 for supporting the same in position. Rod guides 14 and 15 guide the ring rail lift rod in its reciprocating motion, which rod carries the thread board guide 17 and the ring rail 18 for reciprocating movement in the building of the take-up package. A ring is designated 29 and is provided with a traveller 30 through which the yarn passes in being directed to the package on the spindle 20.

A plurality of yarn ends 31 are drawn from supply packages and each passes through an eye 32 which is mounted on an arm 33, pivoted as at 34, and then the group which are to be plied or twisted together pass through the fixed pig-tail guide 35 and extend about the feed rolls in the unit 36 and thence through the pig-tail guide 37 on the thread board 17 to the traveller 30.

The tension of each yarn 31 acting on the guide 32 is such that the arm 33 is held forward, and, as this arm is L-shaped, being weighted as at 38 (see Fig. 3) should the yarn break, arm 33 would move rearwardly or counterclockwise as shown in Fig. 3, about its pivot 34 to press upon the lever 39 (see Fig. 3) which is pivoted as at 40 and has a rod 41 extending downwardly therefrom to enter the feed roll unit 36 which is about to be described.

The feed roll unit 36 (see plan view in Fig. 2 and the sectional view in Fig. 3) has a pair of feed rolls 42 and 43 mounted on the side of the casing 44 which encloses the operating gear mechanism of the unit. A gear 45 is fixed on a shaft 46 which mounts the roll 42, and a gear 47 is fixed on shaft 48 which mounts the feed roll 43. These two gears are connected together by an idler 49 continually in mesh with both of them. The casing is fixed on the twisting frame and the bearings for the shafts 46 and 48 are fixed in the casing.

A driving shaft 50 extends through the casing 44 (see Fig. 4) having a bearing 51 in one wall thereof and a bearing in the bushing 52 located in boss 53 in the other wall thereof for mounting the same. This projecting boss 53 provides an inner bearing surface 54 for an eccentric member 55 which has an enlarged opening 56 therein through which the shaft 50 extends. This eccentric member 55 provides a bearing 57 for a gear 58 to rotate about the eccentric member. This gear is driven from the shaft 50 through an arm 59 fixed thereto by set screw 60 and provided with a pin 61 to extend into a slot 62 in the gear 58 (see also Fig. 7). The eccentric member 55 is provided with a plurality of knobs 63 which may be engaged by a rack 64 provided in the edge of the bar 65 which is mounted by means of rollers 66 and 67 for sliding movement diagonally through the casing 36. As the bar is slid through the casing, the eccentric member 55 is rotated in its bearing 54 so as to move the gear 58 toward and from gear 57 and into and out of mesh therewith.

A cable 70 is attached to the lower end of this bar 65, which cable extends about a drum 71 (see Figs. 1 and 9) mounted on the end of a shaft 72 which has a bearing at 73 provided in the frame 11. The shaft 73 may slide axially of its bearing as well as rotate in the bearing. An enlarged head 74, fixed to the shaft 72, is provided with a slot 75 which receives a pin 76 fixed to the sleeve 77 which encircles the same, while

a spring 78 engaging this head tends to slide the shaft 72 inwardly or to the right, as shown in Fig. 9. Any axial movement to the right, as shown in Fig. 9, will also cause a rotary movement so that the drum 71 will be turned. Thus, tension is applied to the cable 70, tending to draw the rod 65 downwardly through the casing.

As the shaft 72 moves to the right as shown in Fig. 9, its end 79 will engage the abutment 80 on the arm 22 and move the spindle 20 from its position engaging the drive belt 24 away from this belt into engagement with the brake 25 to arrest movement of the take-up spindle. The bar 65 is prevented from being drawn downwardly by the cable 70 by reason of a latch which is carried by the bar and which engages a catch 83 on the casing. In order to cause this engagement of the gears, some means must be provided for lifting this bar so as to release the latch 82. In order to provide a trip for the bar 65 for releasing the latch 82, I have provided a wheel 85 (see Fig. 8) on shaft 48 to revolve therewith. This wheel is somewhat in the form of a ratchet wheel. Another wheel of similar shape, designated 86, is mounted as at 87 upon a part carried by the bar 65. These wheels are in engagement with each other so that rotation of the wheel 85 will drive the wheel 86 when the parts are in normal operating position. However, when the arm 41 drops into the casing from its raised position as shown in Fig. 3, to its lowered position as shown in Fig. 8, then this arm will engage one of the ratchet teeth in wheel 86, as shown in Fig. 8, and arrest its movement, while the rotation of the other wheel 85 will, by reason of the inclined surfaces of its teeth, force the rod 65 away from it or will lift the rod at its outer end, because it is confined by its rack teeth in engagement with the pin 63 at its lower end so as to lift the latch 82 free from its catch 83 and thus permit the rod to be drawn downwardly by the cable for the withdrawal of the gear 58 from driving engagement with the gear 57, the parts being moved to the position shown in Fig. 8 by the dot-dash line circle to the left.

I claim:

1. A yarn handling apparatus comprising a spindle for a take-up package, a feed roll for feeding yarn to the take-up package, a gear fixed on the axis of the feed roll, and a second gear eccentrically mounted and movable into and out of driving relation with said first gear and means for driving said second gear.

2. A yarn handling apparatus comprising a spindle for a take-up package, feed rolls for feeding yarn to the take-up package, a gear fixed on the axis of the feed rolls, a second gear eccentrically mounted and movable into and out of driving relation with said first gear and means for driving said second gear, and means for moving said second gear out of driving relation with said first gear upon breaking of the yarn end.

3. A yarn handling apparatus comprising a spindle for a take-up package, a casing fixed in position relative to said take-up package, a feed roller carried by said casing for feeding yarn to the take-up package, a mounting movably secured to said casing for movement to and from said feed roller, driving means for said roll having an axis parallel to the feed roller and carried by said mounting and movable therewith for moving said driving means laterally of the axis from a roll driving position to a non-driving position, and means for moving said mounting to move said

driving means to a non-driving position upon the breaking of a yarn end.

4. A yarn handling apparatus comprising a spindle for a take-up package, a feed roller for feeding yarn to the take-up package, an eccentric movable mounting, driving means for said roller secured to said eccentric and movable therewith to and from driving position relative to said roll, and means for moving said eccentric to move said driving means to a non-driving position upon the breaking of a yarn end.

5. A yarn handling apparatus comprising a spindle for a take-up package, a casing, a feed roll carried by said casing for feeding yarn to the take-up package, driving means within said casing comprising a member having an axis parallel to said feed roll for rotating said feed roll and movable laterally of said axis to and from driving position with said feed roll, means tending to move said driving means from a roll driving position to a non-driving position, locking means for releasably locking said driving means in the roll driving position, and means for releasing said locking means upon the breaking of a yarn to

permit movement of said driving means to a non-driving position.

6. A yarn handling apparatus as set forth in claim 3 wherein a feed roll for the yarn is provided on a fixed axis in said unit and driving means for the feed roll are moved into and out of driving relation with said feed roll.
